NECKTIE KNOT SUPPORT

Harry Kanter, 535 E. 86th St., New York, N.Y. 10028,
and Robert Kallman, 612 Forest Hills Drive, Wilmington, N.C. 28401

Filed Sept. 6, 1968, Ser. No. 13,418

Term of patent 14 years

Int. Cl. D2—06

U.S. Cl. D2—359

We claim:

The ornamental design for a necktie knot support, as shown.
